[57] CLAIM

The ornamental design for a ice fishing tip up frame, as shown and described.

DESCRIPTION

FIG. 1 is a front perspective view of an ice fishing tip-up frame, showing my new design;

FIG. 2 is a front elevational view, the rear being a mirror image thereof except for the orientation of the flag;

FIG. 3 is a left side elevational view thereof;

FIG. 4 is a right side elevational view thereof;

FIG. 5 is a top plan view thereof; and,

FIG. 6 is a bottom plan view thereof.

FIG.1

FIG 2

FIG. 3
